By his Attorney Phillips Abbott

UNITED STATES PATENT OFFICE

HARRY A. INMAN, OF AMSTERDAM, NEW YORK.

CORNER-STAYING MACHINE.

SPECIFICATION forming part of Letters Patent No. 599,563, dated February 22, 1898.

Application filed June 17, 1897. Serial No. 641,121. (No model.)

To all whom it may concern:

Be it known that I, HARRY A. INMAN, a citizen of the United States, and a resident of Amsterdam, in the county of Montgomery and 5 State of New York, have invented certain new and useful Improvements in Corner-Staying Machines, of which the following is a specification.

My invention relates to improvements in corner-staying machines in making paper boxes, which are applicable to various forms of machines for doing this work, among them to that shown in the Letters Patent granted to Horace Inman and Harry A. Inman March 15, 1896, No. 555,811, to which I refer for a clear understanding of the parts not immediately involved in my present invention, and will confine this specification to a description and illustration of the features constituting it. 20 The invention relates to improvements in the devices which apply the adhesive material by which the stay strip or piece is attached to the corner of the box. Heretofore it has been customary to apply the adhesive material to the strip itself as it was fed to the corner of the box and immediately prior to its application thereto. In some cases the strip of stay material had been previously treated with adhesive substance and then instead of applying the adhesive material itself to the stay immediately prior to its application to the box water or some other liquid has been applied, which had the effect of softening and rendering sticky the adhesive material with which the stay-strip had been previously treated. By my method I apply the adhesive material not to the stay-strip, but to the corner of the box, upon which the stay-strip, which is fed in a dry non-adhesive condition, is applied. This has several advantages, among them the following: The feeding of a stay-strip which is made limp and sticky by the application of paste thereto, or moisture, if the strip has been previously pasted, is more difficult than to feed a dry relatively stiff strip; also, when a pasted strip is fed the feeding mechanism is apt to become gummed up or clogged by the paste and has to be frequently cleaned to keep it in proper working order. I wish it to be understood that I sometimes use a stay-strip which has been treated with adhesive material—

such, for instance, as starch—for the purpose of stiffening it and making it more easy of application by the machine; but when I do 55 use a stay-strip thus stiffened it is always in a dry condition. No moisture is applied to it until it comes in contact with the adhesive material applied upon the corner of the box, so that it has all the advantages of a dry un-gummed strip and none of its disadvantages. 60

By my invention the paste is first applied to the corner of the box, the stay-strip in a dry condition is then applied to the corner, cut off, and pressed down upon it, and then 65 the devices which apply the adhesive material to the box on their return movement coat the exterior surface of the stay-piece (which at this time is attached to the corner of the box) with adhesive material, and when it becomes dry it penetrates the fiber of the stay-strip and greatly increases its strength and 70 the permanence of its attachment to the corner of the box.

Referring to the drawings hereof, Figure 75 1 illustrates an endwise view of the parts of a box-staying machine involved in this invention. Fig. 2 illustrates a sidewise view looking from left to right. Fig. 3 illustrates a perspective of the glue-box and rollers. 80 Fig. 4 illustrates a vertical sectional view of the paste-tank, rollers, and adjacent parts, taken through the center of the roller. Fig. 5 illustrates a side elevation taken from the left, as in Fig. 1, partly broken away to show 85 certain parts in section.

A is the reel for the stay-strip. B is the arm supporting it. C is the box which in my said former patent contains the adhesive material, but in this present instance is merely 90 a support for the feed-rollers D D'. E is the delivery-plate and coacting mechanism referred to in that patent. F is the lower blade of the shears. G is the slideway. H is the slide which carries the grooved compression- 95 roller I. J is the bracket which supports the anvil K, upon which the lower die L is supported. These parts are or may be of any preferred construction. That shown in my said patent and illustrated in the drawings 100 thereof is a desirable construction.

Referring now to the parts which constitute the present invention, a is the glue-box. It is open at its upper end, so that glue or

other adhesive material may be introduced. It is attached to the forward end of the slide H by a plate b, which is attached to the back of the glue-box, and is rigidly held by a screw 5 c, which passes through a slot d in the plate b. This slot is provided so that vertical adjustment may be had when required. The box is square excepting at the front side, where there is provided a diagonal extension 10 e, which is arranged at right-angles to a cut-off corner f of the box. On the inside of the box there is a bracket g, which supports a shaft h, near the forward end of which there is a sleeve or roller i, held in position by a 15 screw j, which passes through the end of the roller and enters the stud or shaft h. Upon the stud h and above the roller or sleeve i there is another sleeve k, which serves to locate the roller i. This roller, as seen best in 20 Fig. 3, projects beyond the inner surface of the projection e through a slot made therein, and its rear or lower side, as seen in Fig. 3, fits closely against, in fact, is practically in contact with, the edge of the slot at that side. 25 At the opposite side, however, on the upper side, as seen in Fig. 3, the periphery of the roller is somewhat removed, say one-sixteenth to one-eighth of an inch from the side of the slot, so that the paste which is within 30 the box would flow therefrom very freely were it not that a scraper or stop device is provided in the following manner:

l is a piece of spring-brass or equivalent material, at the forward or free end of which 35 a little plate m, made at right angles to the spring part l, is formed. The spring is attached, as at n, by a screw or soldered to the side of the paste-box, and is provided with an adjusting-screw o, which passes through 40 a slot p, made in the spring, and the rectangular or flange-like part m is adapted to press snugly against the side of the projecting part e of the glue-box by means of the slot p, and the adjustment of the scraper may be made 45 exact by reason of the screw o. When the screw o is run in, the spring is compressed and the flange-like part m is brought into closer contact with the surface of the roller, thus closing more or less of the slit between 50 the roller and the side of the box e and limiting the supply of the adhesive material. When the screw o is run back, the reverse action takes place. q is another roller, which is supported upon a bracket r, which is fastened to the side and lower end of the glue-box a, and is adapted to revolve upon a stud s, set in the end of the bracket and projecting to the interior of the box a. The roller q likewise projects through a slot made in 55 the angular end f of the box a, and is provided with a scraper t, provided with a rectangular part u and set-screw and slot v, the same as before, by which the amount of adhesive material which can be applied to the box by this 60 roller q is adjusted the same as in the other instance.

The operation of the device is as follows: The stay-strip in a perfectly dry condition is fed from the reel A through the feed-rollers D D' in the same manner as set forth in my 70 said patent. Upon each forward movement of the slideway and the compression-roller I the glue-rollers carried by the glue box or tank, which is properly adjusted vertically and laterally for the purpose, are brought in contact with the diagonally-presented corner of the box and apply adhesive material thereto. At the proper time the stay-strip is fed forward over the corner. The compression-roller I then 75 presses the stay-strip upon the corner, cutting it off at the same time, and by the return movement of the slideway the compression-roller again presses the stay-strip firmly down upon the corner of the box and the glue-rollers apply a second coating of adhesive 80 material upon the outer surface of the stay-pieces. This concludes the staying of that corner. Another corner of the box is then presented to the machine and the operation is repeated. 85

It will be obvious to those who are familiar with this art that modifications may be made in the details of construction without departing from the essentials of the invention. I therefore do not limit myself to such details. 90

I claim—

1. In a corner-staying machine, the combination of a support for the box, feeding devices for the stay-strip, devices to press the strip on the corner of the box, devices to sever the strip and devices to apply adhesive material to the corner of the box, for the purposes set forth. 100

2. In a corner-staying machine, the combination of a support for the box, feeding devices for the stay-strip, devices to press the strip on the corner of the box, devices to sever the strip, and means for applying adhesive material to both sides of the corner of the box, for the purposes set forth. 105

3. In a corner-staying machine, the combination of a support for the box, feeding devices for the stay-strip, devices to press the strip on the corner of the box, devices to sever the strip and devices for applying adhesive material to the corner of the box, arranged in front of the said pressing devices, for the purposes set forth. 115

4. In a corner-staying machine, the combination of a support for the box, feeding devices for the stay-strip, devices to press the strip on the corner of the box, devices to sever the strip, and devices adapted to apply adhesive material to the corner of the box prior to the application of the stay-strip thereto, 120 and subsequently to apply adhesive material to the stay-strip itself, for the purposes set forth.

5. In a corner-staying machine, devices for pressing the stay-strip upon the corner of the 125 box, means to reciprocate the same, a receptacle for adhesive material carried by said

pressure devices, and means to convey the adhesive material from the receptacle to the corner of the box, for the purposes set forth.

6. In a corner-staying machine, a reciprocating device adapted to apply adhesive material to the corner of the box during its movement in one direction, and upon the stay-strips themselves, during its movement in the reverse direction, and means for feeding the stay-strip, severing it, and pressing it upon the corner of the box, for the purposes set forth.

7. A device for applying adhesive material to the corners of boxes, comprising a hollow receptacle, and means for applying the glue to the box supported within the said receptacle and projecting beyond its outer surface, said means arranged to apply the adhesive

material on both sides of the corner, for the purposes set forth. 20

8. A device for applying adhesive material to the corners of boxes, comprising a hollow receptacle, rollers supported within the said receptacle and projecting beyond its outer surface for applying the adhesive material on both sides of the corner of the box, and an adjustable scraper for each of said rollers, for the purposes set forth. 25

Signed at Amsterdam, in the county of Montgomery and State of New York, this 15th 30 day of June, A. D. 1897.

HARRY A. INMAN.
